Primary Examiner — W. A. Teddy Falloway(74) *Attorney, Agent, or Firm* — BACON&THOMAS, PLLC(57) **CLAIM**

The ornamental design for a packaging container as shown and described.

DESCRIPTION

FIG. 1 is a perspective view of a packaging container, showing our new design.

FIG. 2 is a perspective view thereof, shown with the cap separated.

FIG. 3 is a front view thereof.

FIG. 4 is a rear view thereof.

FIG. 5 is a top plan view thereof.

FIG. 6 is a bottom plan view thereof.

FIG. 7 is a right side view thereof; and,

FIG. 8 is a cross section view thereof, taken along line 8-8 of FIG. 3.

In the drawings, the parts represented by the broken lines are not claimed, and the left side view is omitted because it appears the same with the right side view.
